(57) **CLAIM**

I claim the ornamental design for a furniture item with ornamental surface, as shown and described.

DESCRIPTION

FIG. 1 is a first bottom perspective view of a furniture item with ornamental surface, showing our new design;

FIG. 2 is a second bottom perspective view thereof;

FIG. 3 is a third bottom perspective view thereof;

FIG. 4 is a bottom plan view thereof;

FIG. 5 is an enlarged detailed view of FIG. 4;

FIG. 6 is a cross sectional view of the side view of the taken in the direction of section 6-6 of FIG. 5; and,

FIG. 7 is a cross sectional view of the side view of the taken in the direction of section 7-7 of FIG. 5.

The broken lines in the drawings are included for the purpose of illustrating unclaimed features and form no part of the claimed design.

1 Claim, 5 Drawing Sheets
